FIG. 7.

UNITED STATES PATENT OFFICE.

ERNEST C. HEAD, OF VAN WERT, OHIO, ASSIGNOR TO COLBURN MACHINE TOOL COMPANY, OF FRANKLIN, PENNSYLVANIA, A CORPORATION OF PENNSYLVANIA.

SPEED-CHANGING DEVICE.

1,343,131.

Specification of Letters Patent.

Patented June 8, 1920.

Application filed November 10, 1917. Serial No. 201,244.

To all whom it may concern:

Be it known that I, ERNEST C. HEAD, a citizen of the United States of America, and a resident of Van Wert, Ohio, have invented 5 a new and useful Improvement in Speed-Changing Devices, which invention is fully set forth in the following specification.

This invention relates to speed-changing devices for machine-tools, and while capable 10 of use in a wide variety of places, has especial utility in controlling the table drive of a vertical boring and turning mill.

An object of the invention is to provide a controlling device for speed-changing gears 15 which is simple in construction, efficient in operation, and easy of manipulation.

A further object of the invention is to provide a device of the type characterized that may be operated by the workman at his 20 normal position with respect to the machine and which will there indicate to such workman the precise position of the change-speed gears.

Another object of the invention is to provide the movable members of speed-changing gears operatively-related in series with a controlling device comprising a single disk so constructed as to constitute a plurality of cams whereby the said speed-changing gears 30 may be actuated by the rotation of said single disk.

Other objects will appear as the description of the invention proceeds.

The invention broadly considered comprises, in a speed-changing device for machine-tools, change-speed gearing including a plurality of change gears operatively-related in series, and means for controlling the same comprising a rotatable disk constructed to constitute a plurality of cams and connections coacting with said cams and operated by the rotation of said disk to selectively actuate said change-gears. In its preferred embodiment, the change-speed 40 gearing comprises a plurality of operatively-related gears a portion of which are shiftable to selectively engage other gears thereof, and said disk is provided on its opposed faces with cam grooves to shift said shiftable gears. Means are also preferably provided to indicate to the operator the position of said shiftable gears.

The invention is capable of receiving a variety of mechanical expressions, one of which 55 is shown on the accompanying drawings, but

it is to be expressly understood that the drawings are for purposes of illustration only and are not to be construed as a definition of the limits of the invention, reference being had to the appended claims for that purpose.

In said drawings:—

Figure 1 is a side elevation of a portion of a vertical boring and turning mill equipped with a speed-changing device in accordance 65 with the present invention, the elements of said device having surface shading applied thereto to distinguish them from the other elements of the machine;

Fig. 2 is an elevation of the lever elements 70 of said device, the cam disk being shown in dotted lines;

Fig. 3 is an elevation of one face of the cam disk;

Fig. 4 is a face view of the actuation box; 75

Fig. 5 is a central vertical section of said box, showing the cam-actuating gears in elevation;

Fig. 6 is a side elevation of the gears contained in the speed box of the table drive; 80

Fig. 7 is a horizontal section through said speed box showing the gears therein in plan;

Figs. 8 and 9 are details of the speed-changing gears.

Referring in detail to said drawings, 85 wherein the same reference characters are used to designate corresponding parts throughout the several figures, the speed-changing device of the present invention is shown as applied to a vertical boring and 90 turning mill, and particularly to controlling the speed-changing gears in the drive of the table of such mill, but it is to be expressly understood that the invention is not limited in its application to any particular form of 95 machine-tool but is capable of use in a wide variety of places where speed-changing gears of the type in question are to be controlled.

In the form shown in Fig. 7, 1 is the drive 100 shaft for driving the change speed gears in the box 2, located in the embodiment illustrated at the extreme rear of the machine. Mounted for reciprocation upon said shaft 1 within said box 2 are two gears 3 and 4 105 which, together with the flange 5, constitute a unitary gear member provided with a spline received in the seat 6. Also mounted within the box 2 and parallel to the shaft 1 are two shafts 7 and 8. Shaft 7 carries 110

three gears 9, 10 and 11 fixed thereto. Gear 10 may mesh with gear 4 and gear 11 with gear 3. Mounted for reciprocation on shaft 8 and splined thereto are two gears 12 and 13 constituting a unitary gear member and designed to mesh with gears 9 and 10 respectively. Gear members 3, 4 and 12, 13 together with the intermediate gears 9, 10, 11 therefore constitute a plurality of change-gears operatively-related in series. Shaft 8 also carries bevel gear 14 which meshes with bevel gear 15 from which, in the present instance, the table of the mill is driven.

In the form shown, to suitably shift gears 3 and 4 and 12 and 13, two longitudinally movable rods 16 and 17 are mounted for reciprocation within the box 2, the former being provided with a jaw 18 which engages flange 5 and the latter being provided with 20 a jaw 19 which engages gear 12.

Box 2 is shown as provided exteriorly with a bracket 20 which supports rotatably a solid shaft 21 and a tubular shaft 22, the shaft 21 being received within the bore of 25 shaft 22. Pinned to shaft 21 is an arm 23 which at its opposite end is operatively connected to rod 16. Mounted upon shaft 22 is a similar arm 24 operatively connected at its opposite end to rod 17. Shafts 21 and 22 are also provided at their opposite ends with arms 25 and 26 respectively, carrying rollers 27 and 28 for coaction with the cam grooves 29 and 30 upon the opposed faces of a rotatable disk 31. Disk 31 is therefore 30 so constructed as to constitute a plurality of cams. While the cams are shown in the form of grooves in the opposed faces of disk 31, it is to be understood that such a construction is not essential, as by suitable variation 35 they could be formed in the same face or could take the form of raised cam guides, or even cam faces.

Cam disk 31 is mounted on shaft 32 which, in the form shown in Fig. 1, extends to the 45 front of the mill where, in a position convenient to the operator's normal location, it is provided with a suitable operating device and also, preferably, a suitable indicating device. In the form shown, said 50 shaft at its forward end carries a gear 33, which may be a helical gear, contained within the actuation box 34. Within said box is also mounted a pinion 35, shown as a helical pinion, in mesh with gear 33 and carried 55 upon a shaft 36 which extends to the exterior of said box 34 and is there provided with a suitable operating crank 37. Shaft 32 also preferably carries exteriorly of the box 34 a pointer 38 for coaction with suitable 60 indicating characters on the cover 39 of said box.

In the embodiment of the invention illustrated on the drawings, the ratio between gears 35 and 33 is four to one, so that a 65 complete revolution of gear 35 will produce

a quarter revolution of gear 33 and shaft 32. The cam grooves 29 and 30 are so shaped that, upon each quarter revolution of the disk 31 to the positions indicated by the pointer 38 and the letters A, B, C and D 70 on the cover 39, gear member 3, 4 and gear member 12, 13 are shifted to simultaneously-operative positions to secure any one of the four combinations of said gears whereby the shaft 8 may be driven from the shaft 1 at 75 any one of four different speeds. Thus the shaft 8 may be driven from shaft 1 through any one of the four following trains:—gears 3, 11, 10, 13; gears 3, 11, 9, 12; gears 4, 10, 13; gears 4, 10, 9, 12. 80

Therefore it will be perceived that a speed-changing device for machine-tools has been provided comprising a minimum number of parts, and one that is both convenient of manipulation, owing to the location of its manual operating-device at the operator's station, and simple in construction, owing to its control of the change-speed gears from a single disk so constructed as to constitute a plurality of cams. 85

While the embodiment illustrated on the drawings has been described with considerable particularity, it is expressly understood that the invention is not to be restricted thereto but is capable of receiving a variety 90 of mechanical expressions, some of which will readily suggest themselves to those skilled in the art, while certain features thereof are capable of use without other features thereof. Furthermore, while in the 95 illustrated embodiment but two sets of shiftable gears have been controlled, it will be apparent that more than two sets may be shifted by suitable modification of the controlling device. Reference is therefore to 100 be had to the claims hereto appended for a definition of the limits of the invention. 105

What is claimed is:—

1. In a speed-changing device for machine-tools, a driven shaft, change-speed gearing in the drive of said shaft, said change-speed gearing comprising a plurality of simultaneously operative gear members having respectively a plurality of operative positions, and means to adjust said gear members to drive said shaft selectively at different speeds, said adjusting means comprising a single rotatable disk constructed to constitute a plurality of cams, connections whereby the rotation of said cams shifts the 115 respective gear members, and means to rotate said disk.

2. In a speed-changing device for machine-tools, a driven shaft, change-speed gearing in the drive of said shaft, said 120 change-speed gearing comprising a plurality of simultaneously-operative gear members having respectively a plurality of operative positions, and means to adjust said gear members to drive said shaft selectively at 125 130

different speeds, said adjusting means comprising a single rotatable disk having its opposed faces constructed to constitute a plurality of cams, connections whereby the 5 rotation of said cam shifts the respective gear members, and means to rotate said disk.

3. In a speed-changing device for machine-tools, a driven shaft, change-speed gearing in the drive of said shaft, said 10 change-speed gearing comprising a plurality of simultaneously-operative gear members having respectively a plurality of operative positions, and means to adjust said gear members comprising a single rotatable disk 15 constructed to constitute a plurality of cams, means coacting with said cams and directly connected with the respective gear members to shift the same, and means to rotate said disk, the rotation of said disk 20 selectively effecting the movement of all said gear members to their several operative positions.

4. In a speed-changing device for machine-tools, a driven shaft, change-gears operatively-related in series in the drive of 25 said shaft and comprising a plurality of members having a plurality of operating positions, and means for adjusting said members comprising a single rotatable disk constructed to constitute a plurality of cams, means coacting with said cams and connected with the respective members to 30 actuate the same, and means to rotate said disk.

5. In a speed-changing device for machine-tools, a driven shaft, change-speed gearing in the drive of said shaft comprising a plurality of shiftable gear members, and means to adjust said gear members comprising a single disk mounted for continuous 40 rotation in either direction and constructed to constitute a plurality of cams, connections whereby the rotation of said cams shifts the respective gear members, and means to rotate said disk continuously 45 in either direction.

6. In a speed-changing device for machine-tools, a driven shaft, change-speed gearing in the drive of said shaft comprising a plurality of shiftable gear members, and means to adjust said gear members comprising a single disk mounted for rotation 50 and constructed to constitute a plurality of continuous cams, connections whereby the rotation of said cams shifts the respective gear members, and means to rotate said disk.

7. In a speed-changing device for machine-tools, a driven shaft, change-speed gearing in the drive of said shaft, said 55 change-speed gearing comprising a plurality of simultaneously-operative gear members respectively having a plurality of operative positions, and means for adjusting said gear members comprising a single rotatable disk constructed to constitute a plurality of cams, connections whereby the 60

rotation of said cams shifts the respective gear members, means to rotate said disk, and means to indicate the positions of said gear members.

8. In a speed-changing device for machine-tools, a driven shaft, change-speed gearing in the drive of said shaft, said change-speed gearing comprising a plurality of unitary gear members respectively having a plurality of operative positions, and 70 means for adjusting said gear members comprising a single rotatable disk constructed to constitute a plurality of cams, connections whereby the rotation of said cams shifts the respective gear members, and means to 75 rotate said disk comprising a manually-operable device and speed reducing gearing between said device and said disk.

9. In a speed-changing device for machine-tools, a driven shaft, change-speed gearing in the drive of said shaft, said change-speed gearing comprising a plurality of shiftable gear members, rectilinearly movable elements for shifting the respective gear members, a single rotatable disk constructed 85 to constitute a plurality of cams, concentric shafts provided with arms operatively-related to said cams and said gear members, and means to rotate said disk.

10. In a speed-changing device for machine-tools, a driven shaft, change-speed gearing in the drive of said shaft comprising a plurality of shiftable gear members, concentric shafts operatively connected to the respective gear members, a single rotatable disk constructed to constitute a plurality of cams, operative connections between 90 said cams and the respective shafts, and means to rotate said disk.

11. In a speed-changing device for machine-tools having change-speed gearing remote from the operator's normal position at the machine, said change-speed gearing comprising a plurality of shiftable gear members, means to adjust said gear members 105 comprising a single rotatable disk constructed to constitute a plurality of cams, connections whereby the rotation of said cams shifts the respective gear members, a shaft for rotating said disk extending to the operator's position at the machine, means at 110 said position for rotating said shaft, and means at said position for indicating the positions of said gear members.

12. In a speed-changing device for machine-tools having change-speed gearing remote from the operator's normal position at the machine, said change-speed gearing comprising a plurality of shiftable gear members, means to adjust said gear members 115 comprising a single rotatable disk constructed to constitute a plurality of cams, connections whereby the rotation of said cams shifts the respective gear members, a shaft for rotating said disk extending to the operator's position at the machine, means at 120 said position for rotating said shaft, and means at said position for indicating the positions of said gear members.

- erator's position at the machine, a pointer on said shaft for indicating the positions of said gear members, and means comprising speed-reducing gearing for rotating said shaft.
13. In a speed-changing device for a boring mill having change-gears operatively-related in series and comprising a plurality of shiftable gear members in the table drive, means for adjusting said gear members comprising a single rotatable disk constructed to constitute a plurality of continuous cams, connections whereby the rotation of said cams shifts the respective gear members, and means to rotate said disk.
14. In a speed-changing device for a boring mill having change-speed gearing in the table drive, said change-speed gearing comprising a plurality of simultaneously-operative gear members which have a plurality of operative positions, means for adjusting said gear members comprising a single rotatable disk constructed to constitute a plurality of cams, connections whereby the rotation of said cams shifts the respective gear members, and means to rotate said cam.

In testimony whereof I have signed this specification.

ERNEST C. HEAD.
